UNITED STATES PATENT OFFICE.

ULRICH BAUMANN, JR., OF WOODCLIFF, NEW JERSEY.

FABRIC-DYEING MACHINE.

Application filed August 14, 1925. Serial No. 50,175.

This invention relates to improvements in dyeing machines, and has particular reference to a machine for dyeing textile fabrics.

An object of the invention is to provide 5 an improved machine wherein a plurality of tubs containing various liquids utilized in the dyeing process are assembled and into which pieces of fabric are successively conveyed so as to subject said fabric to the 10 action of the baths or solutions in said tubs.

Another object is to control the feeding of a fabric to the various baths in such manner that the fabric, after immersion in one of the baths for a period of time, is, at the 15 termination of such period, automatically transferred to and immersed in a succeeding bath.

A further object is to provide an apparatus which will lift a fabric supporting drum 20 from one tub and deposit the same upon a platform for movement to a succeeding apparatus which is thereupon operable to lower the drum into another tub.

The above and other objects will appear 25 more clearly from the following detailed description, when taken in connection with the accompanying drawings, which illustrate a preferred embodiment of the inventive idea.

In the drawings:—

30 Figure 1 is a fragmentary side elevation of the machine constructed in accordance with the invention;

Figure 2 is a fragmentary top plan view thereof;

35 Figure 3 is a section substantially on the line 3—3 of Figure 1; and

Figure 4 is an enlarged fragmentary elevation of the drum lifting and conveying mechanism.

40 In the dyeing of textile fabrics it is customary to subject the fabric to a plurality of baths consisting of various solutions utilized to accomplish the different steps in the dyeing process. It is also customary to sub-

45 mit the fabric, depending upon its nature, to the various solutions or baths for predetermined intervals of time. Thus, as a specific example, which, of course, need not be strictly adhered to in carrying out the present in-

50 vention, a fabric may be submitted to the following baths in succession for the stated periods of time, namely, acid, five minutes; water, five minutes; bleaching, fifteen minutes; water, five minutes; soap solution, fifteen minutes; water, five minutes; bleaching,

55 acid, fifteen minutes; water, five minutes; bleaching, fifteen minutes; water, five minutes; acid,

five minutes; water, five minutes; dyeing, five minutes. In cases where the fabric is submitted to the action of solutions for periods of more than five minutes, such as 60 the bleaching and soap solutions, a number of tubs containing the same solution are placed in succession. Thus, where the bleaching is carried on for fifteen minutes three tubs containing the bleaching solution 65 are arranged one following the other, it being understood that the fabric is transferred from one tub to the other at the termination of a predetermined period of time which, in the present example, is five 70 minutes.

In carrying out the invention a plurality of tubs 5 are provided equal in number to the total number of five minute intervals occupied during the dyeing process. These 75 tubs are supported in a row by a suitable framework 6 and are arranged in juxtaposition to each other so as to occupy a minimum space. Secured to opposite sides of the tubs and framework and extending thereabove 80 are a plurality of frames 7 arranged in pairs and each frame having a cross piece 8 arranged in an inclined position and combining with the cross piece of the associated frame to form an inclined platform for a 85 purpose which will presently appear. The pair of frames at the extreme left of Figure 1, which is the inlet end of the machine, are attached partly to the framework 6 of the machine, and partly to the first tub 5, the 90 right-hand extremities of said frames being secured to said tub at approximately the middle thereof. The next pair of frames in the order of succession are secured to the first-named tub and also to the succeeding 95 tub with the longer vertical members of said frames arranged adjacent the shorter members of the preceding frames and forming a space therebetween for a purpose to later appear. The succeeding frames 7 are 100 arranged in a like manner and by this arrangement it will be apparent that the platform formed by each pair of frames will overhang two adjacent tubs with the space 105 between adjacent pairs of frames disposed substantially at the middle of each tub. The pair of frames associated with the last tub at the delivery end of the machine is provided with an extension 9 secured to the framework 6 and forming a horizontal platform upon which the various fabric-carrying drums 11 are finally deposited after 110

passing through the solutions in the different tubs. Secured to each tub 5 on opposite sides thereof and in direct alignment with the adjacent vertical members of the 5 pairs of frames secured to said tub is a set of guide strips 12, preferably formed of angle iron and arranged a distance apart substantially equal to the space between said adjacent vertical members of the frames. 10 Slidably mounted for vertical movement between each set of guide strips 12 and into said space is a rack bar 13, operable to lower a drum 11 into a tub and lift the same therefrom at the termination of a definite 15 period of time. The upper ends of the various rack bars are connected by a drum supporting member or bar 10. At the begining of the operation of the machine the supporting member 10 and the various rack 20 bars 13 are elevated sufficiently to permit a drum 11 to be rolled downwardly on the first platform until the trunnions 14 of drum 11 are resting upon the supporting bar 10. Then, as the bars 10 and 13 are lowered the 25 drum moves along the bar 10, by reason of the inclination of the platform, until the trunnions engage in the space between the shorter end of the first platform and longer end of the next succeeding platform. Continued 30 downward movement of the bars 10 and 13 will then lower the drum 11 into the tub until said trunnions engage the bearings 15 secured to the top of the tub. In this position a portion of the drum containing 35 the fabric which is wound thereon in any suitable manner will be immersed in the solution in the tub 5. Each trunnion 14 may be provided with inner and outer collars 16 which will be effective to prevent shifting 40 of the drum in a direction along its axis while in operation.

The mechanism for operating the bars 10 and 13 at predetermined intervals preferably comprises a horizontally arranged shaft 45 17 mounted in bearings 18 adjacent the tops and on both sides of the tubs 5. At the inlet end of the machine each shaft 17 carries a worm gear 19 which meshes with a similar gear 20 carried by the adjacent end of a 50 transversely extending shaft 21 supported in the framework 6. At one end of the shaft 21 the same is provided with a pulley or other drive 22 which is connected by a belt or equivalent element 23 to a source of power 55 such as a motor (not shown). This motor may be of any standard type capable of being reversed and intermittently driven by means of any well known timing mechanism. Each shaft 17 carries a plurality of gears 24 60 each engageable with one of the rack bars 13 so that when the shaft 17 is rotated in the desired direction vertical movement will be imparted to the various rack bars. Thus when the motor above mentioned is driven 65 in one direction the shaft 17 will be operated

to move the rack bars 13 upwardly and with the bar 10 engaging the undersides of the trunnions 14 the various drums will be lifted from the tubs, and when said motor is reversed the rack bars and consequently the 70 drums supported thereby will be lowered into the tubs. When each drum reaches the extremity of its upward movement, the trunnions thereof engage pivoted arms 24' which, in normal position, form extensions 75 of the upper ends of the platform 8. The trunnions lift the arms which then restore to normal, whereupon they form supports for the drum until the same has rolled downwardly onto the platform proper. 80

While the drums are immersed in the tubs and the trunnions thereof are resting upon their bearings 15, the invention provides means for continuously rotating said drums in order that the fabric on the drums will become thoroughly saturated in the solutions in the various tubs. To this end there is provided a shaft 25 on each side of the tubs mounted in suitable bearings 26 and arranged in parallelism with the shaft 17. 85 The forward end of each shaft has a worm gear 27 meshing with a similar gear 28 carried by the adjacent end of a transversely disposed shaft 29 supported by the framework 6. One end of the shaft 29 carries a pulley 30 supporting a drive belt 31, which is connected to a suitable source of power, such as a motor (not shown). On each shaft 25 there is a plurality of worm gears 32 each of which is designed to mesh with a similar gear 33 carried by one of the trunnions 14 of each drum when the trunnions of said drum are resting in their bearings 15. The shaft 25 is continuously driven so that 90 during the intervals of time that the gears 32 and 33 are meshing the drums will be revolved. When the rack bars 13 are operated to lift the drums from the tubs the initial upward movement of said drums will disengage the gears 33 from the gears 32 95 and thus cause a cessation of the rotation of said drums. 100

Above each of the tubs 5 in which the fabric is cleansed by water there is mounted in any suitable manner a shelf 34 (Figure 1) which supports an apertured water pipe 35 connected to a suitable source of supply. The water from said pipe flows off of the shelf 34 in the form of a spray and onto the fabric so that the latter becomes saturated and cleansed. As the water drips from the fabric it falls to the bottom of the tub and flows therefrom through a drain 36 depending from said tub. 110

Briefly, the operation of the machine is 115 as follows:

With the supporting members 10 and rack bars 13 partially elevated a drum containing a fabric is placed upon the platform of the frames 7 at the inlet end of the ma- 120

chine and said drum is allowed to roll along said platform until its trunnions come in contact with the supporting member. Then as the rack bars 13 are lowered the 5 drum consequently moves downwardly along the platform and finally into the first tub 5. When the gear 33 of the drum engages the gear 32 carried by the shaft 25 rotation of the drum will commence and 10 continue until a predetermined period of time has elapsed at which time the shaft 17, the rotation of which is stopped by the stopping of the motor driving the same when the rack bars have reached the extremities 15 of their downward movement, will again be rotated but in an opposite direction so as to start the upward movement of the rack bars. This upward movement disconnects the drum from the shaft 25 stopping the 20 rotation of the former and the movement continues until the supporting member 10 reaches the extremities of its upward movement, at which time the drum trunnions will engage over the arms 24' and be deposited 25 upon the platform of the second set of frames 7. The operator observing the movement of the rack bars will deposit a second drum upon the first platform about the time that the forward extremity of the 30 bar 10 intersects the plane of the platform so that said second drum will roll down the platform and onto the bar 10. This operation is repeated at the termination of each definite period of time and upon each operation 35 of the rack bars each of the drums is lowered into a tub, elevated therefrom and advanced to the next succeeding tub until each drum has passed through all of the various solutions and been deposited upon 40 the platform 9 at the delivery end of the machine.

What is claimed is:

1. In a machine for dyeing textile fabrics, a plurality of tubs capable of containing 45 various liquids in which a plurality of pieces of fabric are to be immersed, means operable to lower each piece of fabric into the various tubs in definite order of succession and lift the same therefrom, and means for 50 conveying each piece of fabric to one of the tubs after being lifted from the preceding tub.

2. In a machine for dyeing textile fabrics, a plurality of tubs capable of containing 55 various liquids in which a drum-carried fabric is to be immersed, means operable to lower a drum carrying said fabric into the various tubs in definite order of succession and lift the same therefrom, means for conveying 60 said drum to each of the tubs after being lifted from the preceding tub, and means for rotating said drum while the same is in lowered position in said tubs.

3. In a machine for dyeing textile fabrics, 65 a plurality of tubs capable of containing

various liquids in which a plurality of pieces of fabric are to be immersed, mechanism operable to convey each of said pieces of fabric to the various tubs in definite order of succession, and means for operating said 70 mechanism to cause the same to convey each piece of fabric from a tub to the next succeeding one at the termination of a definite period of time.

4. In a machine for dyeing textile fabrics, 75 a plurality of tubs capable of containing various liquids in which a plurality of drum-carried fabrics are to be immersed, mechanism operable to convey each of the drums carrying said fabrics to the various tubs in definite order of succession, means for rotating said drums while the same are in said tubs, and means for operating said mechanism to cause the same to convey each drum from a tub to the next succeeding one at 80 the termination of a definite period of time.

5. In a machine for dyeing textile fabrics, 85 a plurality of tubs capable of containing various liquids in which a plurality of drum-carried fabrics are to be immersed, mechanism operable to convey each of the drums carrying said fabrics to the various tubs in definite order of succession, means for rotating said drums while the same are in said tubs, and means for operating said mechanism to cause the same to convey each drum from a tub to the next succeeding one at 90 the termination of a definite period of time, the operation of the last-named means being effective to disconnect said drums from said 95 rotating means.

6. In a machine for dyeing textile fabrics, 100 a plurality of tubs capable of containing various liquids in which a fabric is to be immersed, supporting means associated with each tub and operable to lower said fabric into said tub and lift the same therefrom, and a platform associated with each tub upon which said fabric is deposited for movement toward the next succeeding tub 105 when said fabric is lifted from the first-named tub.

7. In a machine for dyeing textile fabrics, 110 a plurality of tubs capable of containing various liquids in which a fabric is to be immersed, supporting means associated with each tub and operable to lower said fabric into said tub and lift the same therefrom, and an inclined platform over each tub upon which said fabric is deposited for movement 115 by gravity toward a next succeeding tub when said fabric is elevated from the first-named tub.

8. In a machine for dyeing textile fabrics, 120 a plurality of tubs, capable of containing various liquids in which a drum-carried fabric is to be immersed, supporting means associated with each tub and operable to lower a drum into said tub and lift the same 125 therefrom, a platform associated with each 130

tub upon which a drum is deposited for movement toward the next succeeding tub when said drum is lifted from the first named tub, and means for operating said supporting means at predetermined intervals to lift and lower one of said drums.

9. In a machine for dyeing textile fabrics, a plurality of tubs capable of containing various liquids in which a fabric is to be immersed, supporting means associated with each tub and operable to lower said fabric into said tub and lift the same therefrom, and a platform above each tub upon which said fabric is deposited for movement toward a next succeeding tub when said fabric is lifted from the first named tub, the supporting means associated with said succeeding tub projecting above the platform of the preceding tub when said means is operated to lift said fabric.

10. In a machine for dyeing textile fabrics, tubs arranged adjacent each other and capable of containing various liquids in which drum-carried fabrics are to be immersed, platforms disposed above said tubs and along which the drums carrying said fabrics are movable from one tub to another, drum-supporting means associated with said tubs and operable to lower a drum into each tub and lift the same therefrom to deposit the drum upon an adjacent platform, and continuously driven means operable to rotate said drums when the same are lowered into the tubs.

11. In a machine for dyeing textile fabrics, tubs arranged adjacent each other and capable of containing various liquids in which a drum-carried fabric is to be immersed, means for lowering a drum into and lifting the same from each tub in succession, means to which the drum is connected by the act of lowering the same into a tub for rotating said drum, and means for conveying said drum from one tub toward another subsequent to the lifting of the drum from the first-named tub.

12. In a machine for dyeing textile fabrics, tubs arranged adjacent each other and capable of containing various liquids in which a drum-carried fabric is to be immersed, means for lowering a drum into and lifting the same from each tub in succession, means to which the drum is connected by the

act of lowering the same into a tub for rotating said drum, and an inclined platform upon which said drum is deposited upon being lifted from a tub for causing said drum to move toward a succeeding tub.

13. In a machine for dyeing textile fabrics, tubs arranged adjacent each other and capable of containing various liquids in which a fabric is to be immersed, vertically movable rack bars associated with each tub, a bar connecting said rack bars and operable to support said fabric and lower the same into and lift it from said tub, and an inclined platform extending between adjacent tubs upon which the fabric is deposited when the same is lifted from one tub for causing said fabric to move toward a succeeding tub.

14. In a machine for dyeing textile fabrics, tubs arranged adjacent each other and capable of containing various liquids in which a drum-carried fabric is to be immersed, vertically movable rack bars associated with each tub, a bar connecting said rack bars and operable to support a drum carrying said fabric and lower the same into and lift it from said tub, means for rotating said drum when the same is lowered into a tub, and an inclined platform extending between adjacent tubs upon which the drum is deposited when the same is lifted from one tub for causing said drum to move toward a succeeding tub.

15. In a machine for dyeing textile fabrics, tubs arranged adjacent each other and capable of containing various liquids in which a drum-carried fabric is to be immersed, vertically movable rack bars associated with each tub, a bar connecting said rack bars and operable to support a drum carrying said fabric and lower the same into and lift it from said tub, means for rotating said drum when the same is lowered into a tub, an inclined platform extending between adjacent tubs upon which the drum is deposited when the same is lifted from one tub for causing said drum to move toward a succeeding tub.

In testimony whereof I have affixed my signature.

ULRICH BAUMANN, JR.
